UNITED STATES PATENT OFFICE

SEBASTIEN OTTO ALFRED FIEDLER, OF PARIS, FRANCE, ASSIGNOR TO L'AUXILIAIRE
DES CHEMINS DE FER ET DE L'INDUSTRIE, OF PARIS, FRANCE

FEED-WATER HEATER

Application filed July 27, 1928, Serial No. 295,725, and in France June 15, 1928.

The present invention relates to feed water heaters for boilers, and chiefly to feed water heaters, for locomotive boilers, wherein feed water is mixed with heating steam and it has 5 for its object to provide a feed water heater of this type by which the water will be heated to a temperature exceeding 100°, that is, a feed water heater operating under pressure, while affording the discharge of all excess 10 of heated water without any loss of steam.

The invention relates more particularly to feed water heaters comprising a mixing chamber which is supplied with water to be heated and with heating steam under a certain 15 pressure, and a distribution chamber, these two chambers being connected together by a water joint.

According to the invention, these two chambers are closed and may contain the 20 heating steam under pressure and the part of the distribution chamber which contains the excess of hot water is connected with the atmosphere by a second water joint affording a sufficient difference of level to balance 25 the steam pressure.

When the heating steam is delivered to the feed water heater in a pulsatory manner, the arrangement according to the invention will permit, without loss of steam, the mixing 30 chamber to remain constantly emptied of hot water, this condition being indispensable for the obtainment of the maximum heating and of a constant temperature for the heated water.

Further characteristics of the invention 35 will be specified in the following description, with reference to the appended drawings, wherein Figs. 1 and 2 are diagrammatic views showing by way of example two constructional forms of feed water heaters according to the invention.

As shown in Fig. 1, the feed water heater 40 comprises two main receptacles 1 and 2, receptacle 1 serving as a mixing chamber, and receptacle 2 as a distribution chamber. Heating steam is admitted through a conduit 3 and an oil separator 4 into mixing chamber 1; water to be heated is supplied 45 from the cold water tank (for instance the tender of a locomotive), through a piping 7

and a tube 5 by means of a pump 6. The two chambers are connected together by a bent pipe 8 whose lower end opens into a recess or pocket 19 formed in the bottom of chamber 1.

Hot water is withdrawn at 9 from chamber 55 2 by a pump 10 and is delivered into the boiler through a pipe 11; the excess of hot water overflows into an overflow compartment 12. The two chambers 1 and 2 are provided at the top with respective gas discharge orifices 13, 14 of small size, whereby the gases disengaged from the water by the heating and circulation are discharged without any appreciable loss of heating steam.

The overflow compartment 12 is connected 60 by a U shaped tube 15 with a tank 16 open to the atmosphere at 17 and which may form part of chamber 2 or may consist of a separate receptacle. Said tank 16 is connected by a discharge pipe 18 with the suction 70 piping of the cold water pump.

It will be noted that the feed water heater is substantially closed or fluid tight, with the exception of the orifices 13 and 14, through which the loss of steam is negligible. In 75 these conditions, when the plant is in operation, and as water is heated in chamber 1 by admixture with steam, and collects at the bottom of said chamber and in recess 19, said water will rise in pipe 8 due to the steam pressure and will flow into chamber 2, the pipe 8 forming a water joint between said chambers. The water is withdrawn from the distribution chamber by the hot water pump, and the excess overflows into compartment 80 12 and thence through the U-tube 15 into tank 16 whence it is returned to the suction piping 7 of the cold water pump.

If the steam pressure in the chamber 1 exceeds the pressure corresponding to the 90 height of the joint 8, the steam also enters chamber 2; a difference of level corresponding to the steam pressure will be set up in U shaped tube 15, the water level therein having now lowered to $a-a$ for example. 95 Otherwise stated, the feed water heater may utilize the steam at a maximum pressure corresponding to the sum of the heights of the water joints formed by the respective pipes 8 and 15.

The heating steam can thus be employed at a higher pressure than if the tube 15 were not used, so that the temperature of the water can be raised to a corresponding degree, and 5 without any loss of steam to the atmosphere.

Such an arrangement is particularly advantageous when the steam employed is admitted into the heater in a pulsatory manner, which is the case for example for the exhaust 10 steam from the cylinders of the main engine or from the steam cylinders of auxiliary machines, such as the water pump, air compressor or the like. In this case, at each pulsation of steam, the hot water which has 15 collected in chamber 1 will be forced into chamber 2 through pipe 8; a certain amount of steam also passes into chamber 2, thus forcing the water from compartment 12 into tube 15 as far as the level *a—a* for instance. Chamber 1 is thus constantly emptied of 20 water, or nearly so, and hence the whole capacity of the said chamber is available for the proper admixture of cold water and steam. In this manner, the apparatus operates in the 25 optimum conditions required to obtain the maximum heating of the water. Further, since the volume of water heated in chamber 1 is negligible, variations of this volume have no effect upon the temperature of the heated 30 water, this temperature remaining absolutely constant.

The water joint formed by tube 15 also serves to damp the effect of the pulsations of the steam, since the mass of water contained 35 in this tube is subjected to oscillations corresponding to such pulsations, and, by reason of the inertia of this water, the heating steam may have a pressure slightly above the theoretical pressure corresponding to the 40 maximum difference of level in the tube 15, without danger of loss of steam.

Furthermore, even if the water joint in the tube 15 should be accidentally blown off, whereby steam would escape therethrough, 45 said steam will be discharged into the atmosphere at 17 without causing any prejudicial effect upon the cold water pump suction piping.

Obviously, the construction of the heater 50 may differ from that illustrated in Fig. 1, and for instance it may comprise only a single body or unit (Fig. 2); in this case, the water joint between the mixing chamber 21 and the distribution chamber 22 will consist of two 55 partitions 23 and 24. The operation and the advantages are exactly the same as in the preceding case.

It is further obvious that the said feed water heater is susceptible of numerous modifications without departing from the principle of the invention.

Having now described my invention, what I claim as new and desire to secure by Letters Patent is:

65 1. A feed water heater comprising a sub-

stantially closed mixing chamber adapted to be supplied with heating steam, means for supplying said mixing chamber with feed water to be heated, a substantially closed distributing chamber, a hydraulic joint between 70 said chambers, the weight of the water column forming said joint being adapted to be overcome by the pressure of the heating steam whereby water and steam are caused to flow from said mixing chamber into said distributing chamber, said mixing chamber containing substantially no water, a storage compartment in said distributing chamber adapted to receive the water from said mixing chamber; hot water discharge means in said storage compartment, an overflow compartment in said distributing chamber, adapted to receive the overflow from said storage compartment, and means for discharging water from said overflow compartment and preventing the escape of steam, comprising a hydraulic joint adapted to balance the maximum pressure of the steam in said distributing chamber.

2. A feed water heater according to claim 1, wherein said latter discharging means comprise a U shaped tube whose height is sufficient for balancing the maximum pressure of the steam in said distributing chamber.

3. A feed water heater comprising a substantially closed mixing chamber adapted to be supplied with heating steam, means for supplying said mixing chamber with feed water to be heated, a substantially closed distributing chamber, a hydraulic joint between 90 said chambers, the weight of the water column forming said joint being adapted to be overcome by the pressure of the heating steam whereby water and steam are caused to flow from said mixing chamber into said distributing chamber, said mixing chamber containing substantially no water, a storage compartment in said distributing chamber adapted to receive the water from said mixing chamber, hot water discharge means in said storage compartment, an overflow compartment in said distributing chamber adapted to receive the overflow from said storage compartment, an overflow receptacle open to the atmosphere and a U shaped tube, one branch 95 of said tube opening into said overflow compartment and the other branch opening into said overflow receptacle, the height of said U-shaped tube and receptacle being sufficient for balancing the maximum pressure of the steam in said distributing chamber.

In testimony whereof I have signed my name to this specification.

SEBASTIEN OTTO ALFRED FIEDLER.
